UNITED STATES PATENT OFFICE.

GEORGE A. JORDAN, OF NEW YORK, N. Y., ASSIGNOR OF ONE-THIRD TO WILLIAM H. JORDAN AND ONE-THIRD TO CHRISTOPHER C. JORDAN, BOTH OF BROOKLYN, NEW YORK.

METAL MOLDING.

1,113,560.

Specification of Letters Patent. Patented Oct. 13, 1914.

Application filed December 11, 1912. Serial No. 736,099.

To all whom it may concern:

Be it known that I, GEORGE A. JORDAN, a citizen of the United States, residing in the borough of Brooklyn, county of Kings, city and State of New York, have invented a certain new and useful Metal Molding, of which the following is a specification.

This invention relates to moldings for supporting and inclosing electric wires. It is a 10 simplification of the invention disclosed in my co-pending application for patent filed November 7, 1912, Serial No. 729,936.

The object of the invention is to produce a very cheap and strong molding which will 15 be fire-proof, which may be readily attached in place, to which the capping and fittings may be readily secured, and which will not be unsightly.

These and further objects will more fully 20 appear from the following specification and accompanying drawings, considered together or separately.

In the drawings, Figure 1 is a plan view of a molding, with capping removed, showing 25 one embodiment of the invention. Fig. 2 is a sectional view thereof, showing the capping in place. Fig. 3 is a similar view of a modification. Fig. 4 is a similar view of another modification. Figs. 5 and 6 are 30 sectional views of another modification. Fig. 7 is a plan view of still another modification, and Fig. 8 is a section on the line 8—8 of Fig. 7.

In all of the several views, like parts are 35 designated by the same reference characters.

In carrying out the invention, I make a molding 1, of sheet metal. This molding is trough-shaped, as shown. It may conveniently be stamped or rolled to shape. It is 40 made in sections of suitable length. In connection with the molding is a capping 2, which is of sheet metal in the form of a strip of uniform width. Inside of the molding is a reinforce 3. This reinforce may be 45 made of any suitable material, such as wood. It is in the form of a strip, best made as shown of rectangular cross-section, as wide as the inside depth of the molding. To assist in retaining the reinforce in place, and 50 for the purpose of accurately determining its position, the molding is provided with ridges 4, 4, on each side of the reinforce. These ridges are conveniently made by folding or creasing the metal along parallel 55 lines as shown, so as to produce a shallow

trough in which the reinforce will rest. The reinforce may be further held in position by fastenings, such as nails or tacks 5, passing through the bottom of the molding and entering the reinforce. The capping is affixed to the open side of the molding, inclosing and supporting the wires. It is held in place by means of fastenings, such as nails or tacks 6, which pass through the capping and enter the reinforce. The capping may 60 be made with an alined series of openings for this purpose.

For the purpose of making a close joint at the edges of the capping and molding, and to aline the former in place, the free edges of the molding may be bent outward, forming tables 7, and then upward, forming flanges 8. These flanges are separated a distance equal to the width of the capping. The capping will then rest upon the tables, 75 and its edges will engage the flanges, thus alining it in position, and making a tight and close joint. The capping is sufficiently stiff so that when nailed in place, the wires will be inclosed and supported. Any number of reinforces may be employed. In Fig. 2, one reinforce is shown, and two are illustrated in Fig. 3.

Fig. 4 illustrates a modification where the reinforce 3^a is provided with a center limb 80 3^b, for attachment of the capping, and side limbs, 3^c, 3^d, to support the edges of the capping in lieu of the tables 7, 7.

Figs. 5 and 6 illustrate a modification in which the reinforce is held in position without the use of nails, screws or the like. In this form of the invention the reinforce 3^e, is provided with a foot, 3^f, and the ridges 4^a—4^b, are rolled or bent over the foot, thereby holding the reinforce firmly in position. 90

In Figs. 7 and 8, the reinforce is in the form of blocks 9, each having a flange 10, to which the capping may be secured. The molding 1 is made with inclined sides 1^a, thereby producing a trough which is wider at the bottom than at the top, and the foot of each block 9 has beveled ends 11, corresponding to the inclinations of the sides 1^a. The blocks are inserted at the ends of the molding, and slid along to the desired positions, leaving spaces between them so that the holes through which the molding supporting nails or screws are to be inserted, may be located. If desired, the blocks may be inserted in the molding after it is in posi- 100 110

tion, in which case the trough may be completely filled with the reinforcing blocks.

The molding, in all of the embodiments of the invention, may be supported by fastenings (not shown) which may pass through the bottom where it is not covered by the reinforce, or through the latter, as may be desirable.

In accordance with the provisions of the 10 patent statutes, I have described the principle of my invention, together with the apparatus which I now consider to represent the best embodiment thereof; but I desire to have it understood that the apparatus 15 shown is merely illustrative and that the invention may be carried out in other ways.

Having now described my invention, what I claim as new and desire to secure by Letters Patent, is:—

- 20 1. A molding formed of sheet metal, with parallel ridges in the bottom, a wooden strip within the molding and lying between the ridges, so as to prevent the removal of the strip and a capping of sheet metal attached 25 to the strip.
2. A metal molding, formed of a trough-shaped body, of sheet metal, parallel ridges in the bottom thereof, said ridges being inclined toward each other and tables on the 30 edges, a wooden reinforce lying between the ridges and secured thereby to the body by the ridges in such a manner as to prevent removal of the strip, and a capping of sheet metal secured to the reinforce and resting 35 on the tables.
3. A metal molding, formed of a trough-shaped body, of sheet metal, tables on the

edges thereof, and edge flanges on the sides of the tables, a capping of sheet metal secured to the molding and resting on the 40 tables, and between the flanges.

4. A molding formed of sheet metal, a reinforce within the molding, and inclined members integral with the molding for securing the reinforce between them and the 45 bottom of the molding.

5. A molding formed of sheet metal, a reinforce within the molding, a foot on the reinforce and inclined members engaging over the foot to secure the reinforce in position. 50

6. A molding formed of sheet metal, a reinforce within the molding, a foot on the reinforce and inclined members integral with the molding, engaging over the foot to 55 secure the reinforce in position.

7. A molding formed of sheet metal, the bottom of the molding being creased, a reinforce secured between the creased portions and a capping secured to the molding. 60

8. A molding formed of sheet metal, the bottom of the molding being creased to form parallel ridges, the ridges being inclined toward each other, a reinforcement within the molding, a foot on the reinforcement, said ridges engaging over the foot, and a capping secured to the molding. 65

This specification signed and witnessed this 6th day of December, 1912.

GEORGE A. JORDAN.
